(57) **CLAIM**

The ornamental design for a case for toy beads, as shown and described.

DESCRIPTION

FIG. 1 is a perspective view of a case for toy beads showing my new design;

FIG. 2 is a front view thereof;

FIG. 3 is a top view thereof;

FIG. 4 is a bottom view thereof;

FIG. 5 is a right side view thereof; and,

FIG. 6 is a left side view thereof.

The broken lines shown in the figures illustrate portions of the case for toy beads that form no part of the claimed design.

1 Claim, 6 Drawing Sheets
